UNITED STATES PATENT OFFICE.

JACOB M. LEE, OF HOUSTON, TEXAS.

STOCK-GUARD.

SPECIFICATION forming part of Letters Patent No. 614,013, dated November 8, 1898.

Application filed March 7, 1898. Serial No. 672,959. (No model.)

To all whom it may concern:

Be it known that I, JACOB M. LEE, a citizen of the United States, residing at Houston, in the county of Harris and State of Texas, have invented certain new and useful Improvements in Stock-Guards; and I do hereby declare the following to be a full, clear, and exact description of the invention, such as will enable others skilled in the art to which it appertains to make and use the same.

The object of the invention is to provide an improved guard of effective form and cheap construction which can be readily secured to the road-bed (cross-ties) of a railroad without the necessity of removal therefrom, in order to make such track repairs as are required, except the renewal of cross-ties, in which event it will only be necessary to remove that portion of the guard attached to the specific tie to be renewed.

The invention consists, in combination with the ties of the road-bed, of sheets of metal covering for said ties, which lie on the chamfered or beveled edge of the ties and extend over the top of the ties in an angular form, so as to produce a series of slanting or beveled surfaces, which surfaces are provided with a row or rows of sharp-pointed teeth near their lower edges, said teeth projecting upward and outward in vertical planes normally at right angles to the length of the covering on the ties, and an angle-iron or other suitable device nailed to the ties lengthwise of the track, so as to separate the ties and keep them apart such a distance as will conform to the size of the hoofs of horses and cattle. These coverings or angular caps, provided with teeth as above described, are placed on the ties both inside and outside of the rails.

Reference is had to the accompanying drawings, in which the same parts are indicated by the same letters throughout the several views.

Figure 1 represents a transverse section across the track. Fig. 2 represents a section across the cross-ties, but parallel to the track, and represents a section made by the plane 22 in Fig. 1; and Fig. 3 represents an enlarged detail sectional view of one of the cross-ties with its cattle-guard secured thereto.

A represents the track-rails, and B the

cross-ties. Since in a cattle-guard of the character herein described it becomes desirable to have the cross-ties spaced at the proper distance apart, I preferably provide for this purpose angle-irons C, which may be nailed to each cross-tie, and thus hold the same spaced at the proper distance.

D represents the cattle-guards, preferably in the form of inverted V's, with teeth d stamped out of the sides and projecting over into the space between the cross-ties. These cattle-guards D are secured to each cross-tie not only between the tracks, but also on either side thereof, as shown in Fig. 1.

E represents the side guards, preferably constructed in the ordinary way.

By referring to the drawings it will be seen that an animal attempting to cross the guard will find no footing except in the spaces between the ties, which are cleared of ballast or earth to or near the bottom of the ties. These spaces are so arranged relative to the size of the hoof that the weight of the animal in causing the depression of the postern-joint brings the fetlock or rear portion of the leg between the fetlock and hoof in contact with the points of the teeth, thereby necessitating the withdrawal of the foot.

Each cap or metal covering being attached independently to the ties it can readily be seen that all repair-work incident to the movement of trains—such as lining, surfacing, tamping, raising, &c., except the actual renewal of ties—can be done without removing the guard, either in whole or part, from the road-bed. This feature is one of great importance in facilitating trackwork and economizing time and labor.

Should one or more of the caps become injured, the independent attachment to the ties facilitates renewal or repair without disturbing the rest of the guard.

Having thus described my invention, what I claim, and desire to secure by Letters Patent of the United States, is—

1. A cattle-guard adapted to be secured to the tops of a series of cross-ties, consisting of a plurality of inverted-V-shaped metallic pieces having teeth stamped out of one or both edges thereof and projecting upward and outward into the spaces between the cross-ties, substantially as described.

2. The combination with a plurality of cross-ties spaced at approximately the same distance apart and chamfered on their upper edges, of inverted-V-shaped metallic pieces secured to the tops of the cross-ties and provided with teeth projecting outward and upward over into the space between the cross-ties, substantially as and for the purposes described.
- 10 3. The combination with a plurality of cross-ties chamfered on their upper edges, and angle-irons secured to the said cross-ties, and spacing the same at approximately equal distances from each other, of a plurality of inverted-V-shaped metallic pieces secured to the tops of the cross-ties and provided with

sharp teeth projecting upward and outward into the space between the cross-ties, substantially as and for the purposes described.

4. A cattle-guard consisting of a plurality of pieces of metal made in the form of an inverted V provided with teeth stamped out of the sides thereof and secured to each cross-tie between the track-rails and outside of the same, substantially as and for the purposes described.

In testimony whereof I affix my signature in presence of two witnesses.

JACOB M. LEE.
